UNITED STATES PATENT OFFICE.

LUCIUS DIMOCK, OF LEEDS, MASSACHUSETTS.

PORTABLE EMBROIDERY-HOOP HOLDER.

SPECIFICATION forming part of Letters Patent No. 663,424, dated December 11, 1900.

Application filed August 24, 1900. Serial No. 27,934. (No model.)

To all whom it may concern:

Be it known that I, LUCIUS DIMOCK, a citizen of the United States, and a resident of Leeds, in the county of Hampshire and State of Massachusetts, have invented certain new and useful Improvements in Portable Embroidery-Hoop Holders, of which the following is a specification.

My improvements relate to details having for their object generally an increased holding power in the hoop-clamping jaws, an increased facility in operating the holder, and a construction combining great strength with little weight; and the invention consists in the combination and arrangement as herein-after described and more particularly pointed out in the claims.

My invention is fully illustrated in the accompanying drawings, in which—

20 Figure I is a side elevation of my device combined with a table and having the clamp-jaws open. Fig. II is a side elevation of a portion of the device in partial section and showing the clamp-jaws closed upon the hoops. Fig. III is a front elevation of a portion of the holder with its jaws open. Fig. IV is a top plan view of the holder, and Fig. V is a detail view of a part of the device.

Referring to the drawings, A is the lower section of the holder, comprising at its rear end and integral with it a clamp B, adapted to secure the device to a table or other support, a shank C, extended horizontally from the clamp B, a hoop-holding jaw D upon the end of the shank, and an upward extension or flange E from the shank C.

A screw-socket for a vertical clamp-screw F is provided in the shank intermediate to the jaw D and flange E, and in line with this 40 socket and flange and upon the top of the clamp B are a bearing-surface *a* and retaining-screw and washer for the pivot end of the upper section provided with the hoop-holding jaw G, opposing the one D.

45 The clamp B is of the usual construction, as more particularly shown in Fig. I, with its clamp-screw H binding the device to the edge of a table I, and needs no further description.

The jaws of clamp B, the bearing-surface *a* above it, the upward extension E, the shank C, and the lower jaw D of the hoop-clamp are

all formed of one metal casting, and, as shown in the drawings, the lower hoop-jaw D is united to clamp B by a web forming a bracket combining little weight with the firmest support to the hoop-holding clamp. 55

The upper section of the holder comprises the hoop-jaw G, a bifurcated rear extension in the same plane with the jaw adapted to inclose the flange E, and terminal ends to this 60 extension J, adapted to bear and pivot upon the surface *a*, so that the upper section when clamping the hoops K K', as shown in Fig. II, between its jaw G and the one D bears only 65 on the tops of the hoops and the surface *a*.

The clamp-screw F, as shown more particularly in Fig. II, has its lower end received in a nut-socket in the lower section A, while a shoulder above an unthreaded portion of the screw bears upon the top of the upper section. 70 A coil-spring *s* incloses the stem of the screw, with its ends bearing, respectively, upon the two sections, so that as the jaws of the clamp are released by the screw F the upper one is borne away from the lower by the action of the spring, and the mouth of the clamp 75 is held open, as shown in Fig. I, to receive the hoops with their inclosed fabric.

In Figs. I, IV, and V the forked ends of extension J are shown held to the bearing-surface *a* by the projecting flange of a washer *v*, held by a screw *w*, passing into the surface *a*, midway between the forked ends. The washer being the equivalent of a larger screw-head, play enough is given by the washer to 85 the forked ends to permit them to pivot upon the bearing-surface beneath them, while effectively preventing them from kicking upward when the jaw G is brought into operation. By this form of constructing extension J 90 when it is necessary to remove jaw G to clean the device or for other reasons it is only necessary to remove screw F, when the jaw can be slid off flange E and from beneath washer *v*. The flange E serves to insure the proper 95 movement to jaw G relative to its opposing one, while entirely relieving screw F of the lateral strain it would be subjected to had it to serve as a guide, and in that way adds materially to the life of the device, as well as to 100 its efficiency, by preventing the clamp-screw F from binding in operation and so permit-

ting one hand to perfectly manipulate the clamping-jaws, while leaving the other hand free to hold the hoops containing the work.

The construction of the hoop-holding jaws 5 to insure the firmest grip, to readily take in various sizes of hoops, and to permit the hoops to be inserted in the shortest time and with the minimum amount of care is as follows: Both jaws D and G are, as shown in Fig. IV, extended segments of the largest hoop that would ordinarily be used, and their bearing-surfaces are deep enough to clamp the smallest hoops. The lower jaw D is provided at the rear of its bearing-surface with 10 an upright flange d of less depth than the hoops, which flange serves as a guide or stop, enabling the hoops inclosing fabric to be simply inserted in the open mouth of the clamp and pushed back until they bear against the flange. It also serves as a guard to prevent 15 projecting edges of the fabric in the hoops from coming in contact with screw F and interfering with its operation or from becoming themselves soiled from lubricant used upon 20 the screw.

As shown in Fig. III in exaggeration for the sake of better illustration, the bearing-surface of clamp-jaw G is formed concave, so that the first action of screw F in clamping 25 the jaws is to overcome a spring in the jaw before bringing it to a continuous bearing on the hoops. This insures the outer extremities of the jaws binding with equal force with their central parts immediately under the 30 screw and is regarded as important. The depth of the concavity does not have to be great and is effected in a casting, and it is immaterial in which jaw the concavity is formed.

By these means I construct a light easily- 35 operated hoop-holder and one strong enough to easily support upon the fabric within the hoops the hand of the workman.

Now, having described my invention, what I claim is—

1. In a hoop-holder of the class described, 45 the combination with a lower section comprising a bench-clamp, an outward-extending shank therefrom, a segmental clamp-jaw upon said shank provided with a surface adapted to seat the hoops upon their edges, a guiding-flange above said shank, a pivot-bearing surface above the bench-clamp, and a screw-socket intermediate to the guide-flange and segmental jaw, of an upper section comprising an opposing segmental jaw adapted to co-operate with the lower jaw in clamping the hoops upon their edges, provided with a rearward bifurcated extension inclosing the guiding-flange, and with extremities adapted to pivot above the bench-clamp, and a spring- 50 inclosed clamp-screw for drawing the jaws together and throwing them apart when released.

2. In an embroidery-hoop holder, the combination with a lower section comprising a 55 bench-clamp, an outward-extending shank therefrom, a segmental clamp-jaw upon said shank provided with a guide-rim, as described, and adapted to bind upon the edges of the hoops, a bearing-surface located above 60 the bench-clamp, a screw-socket in rear of the segmental clamp, and a guide-flange between the screw-socket and pivot-bearing, of an upper section comprising a segmental jaw for opposing the lower one, having a pivoted end 65 confined as described to its bearing-surface, a bifurcated shank embracing the guide-flange, and a clamp-screw and spring operating to close and throw open the segmental jaws, all operating as shown and described. 70 75 80

LUCIUS DIMOCK.
